UNITED STATES PATENT OFFICE.

JOHN CHARLES MILLER, OF SAULT STE. MARIE, ONTARIO, CANADA.

DESIGN FOR A RACK.

51,987.

Specification for Design.

Patented Apr. 23, 1918.

Application filed December 19, 1916. Serial No. 137,920. Term of patent 7 years.

To all whom it may concern:

Be it known that I, JOHN C. MILLER, a subject of the King of England, residing at Sault Ste. Marie, Algoma, Ontario, Canada, have invented a new, original, and ornamental Design for a Rack, of which the following is a specification, reference being had to the accompanying drawing, forming part thereof.

The figure is a perspective view of a rack, showing my new design.

I claim:

The ornamental design for a rack, as shown.

JOHN CHARLES MILLER.

Witnesses:

JAMES LELAND DARLING,
C. A. BATSON.
